UNITED STATES PATENT OFFICE.

JOHN W. PAUL, OF KITTANNING, PENNSYLVANIA.

TYPE-WRITER.

No. 889,632.

Specification of Letters Patent.

Patented June 2, 1908.

Application filed July 5, 1906. Serial No. 324,904.

To all whom it may concern:

Be it known that I, JOHN W. PAUL, a citizen of the United States, residing at Kittanning, in the county of Armstrong and State of Pennsylvania, have invented new and useful Improvements in Type-Writers, of which the following is a specification.

This invention relates to typewriters and consists in certain improvements in the construction thereof as will be hereinafter fully described and pointed out in the claims.

More particularly the invention relates to improvements in the marginal stops and line lock of the machine.

15 The invention is illustrated in the accompanying drawings as follows:

Figure 1 shows a front elevation of the typewriter with my invention in place thereon. Fig. 2, a front elevation of a fragment 20 of the machine including the marginal stops and line lock. Fig. 3 is a section on the line 3-3 in Fig. 2. Fig. 4, a side elevation partly in section showing the same parts.

A marks the platen of the machine; A', 25 the carriage. In the drawings shown the fragment of the platen is shown and one of the rods of the carriage. The construction of these parts are not peculiar to this invention and are well understood in the art.

30 B marks the ribbon spools; B', the ribbon; C, the type guide; D, the type bar basket; and E, the key levers.

The typewriter shown is a "front strike" machine and while the broader features of 35 my invention are applicable to other types of machines, it is particularly adapted to a "front strike" machine.

The scale F is secured to the carriage and carried with it in any desired manner (not 40 shown) and operates in the manner of such scales ordinarily used in that it indicates the position of the carriage and the printing point. The pointer H is mounted on one of the carriage guides G. As shown the 45 scale is arranged immediately in front of the type basket and in full view of the operator together with the printing point on the platen at all times. The pointer H comprises the plate h' which is secured to the guide rod G by means of the screws h. This plate extends downwardly and at the 50 bottom is bent up having a slot h² formed therein, making the arms h³ at the sides

of the slot. These arms extend upwardly and unite in the finger h⁵ forming the pointer proper. This pointer is arranged immediately in the middle of the machine directly under the printing point and over the scale F. A lock lever I is pivoted on the pin i'. The pin i' is secured to a portion of the 5 frame K. At the bottom of this lever there is the opening i³ through which the universal bar L passes. In this opening there is the locking shoulder i⁴ and the depression i⁵. A spring i² is tensioned between the lever I 60 and the frame K and tends to hold the lever in the position shown in Fig. 2, so that the universal bar will be over the depression i⁵. With the universal bar in this position it 65 may be readily depressed and the machine operated. When however the lever is swung so as to bring the shoulder i⁴ of the rocking lever under the universal bar L, the parts are locked against operation.

I place the marginal stops directly on the 75 scale F. By this means the scale F not only indicates the position of the carriage but also indicates the adjustment of the marginal stop. The marginal stop J comprises the plate j. The ears j' are bent over the scale F 80 as clearly shown in Fig. 3, so as to secure the plate j in place on the scale and still permit it to slide thereon. The scale F is provided with a series of notches f one for each space and a pin j⁵ on the marginal stop is adapted 85 to enter these notches. The pin j⁵ extends through the slot j² in the plate j and is secured in a latch j³. The latch is pivoted at j⁴ on the plate. It is provided with a shoulder j⁷ against which the spring j⁶ is tensioned. 90 The action of this spring normally holds the pin j⁵ in one of the notches f so as to lock the plate j or the marginal stop in position on the scale. When it is desired to shift the marginal stop, the latch j³ is depressed, thus carrying the pin j⁵ out of engagement with the scale and the stop may then be moved in either direction as desired. The end of the stop j¹⁰ will indicate on the scale the space at 95 which the stop will act. There are preferably two of these stops, one for each margin, each a duplicate of the other except the direction of the parts are reversed. The upper end of the lever I is arranged in the path of the shoulder j⁸ of the stop J so that as the 100 stop is moved with the carriage, it contacts

the lever I and swings it so as to bring the locking shoulder j^4 under the universal bar. This will be accomplished just as the pointer H is in line with the end of the stop.

5 The lever I is provided with slots i . A pin h^4 extends through the finger or pointer proper h^5 and also through this slot i . It is free to slide in the slot but is locked against withdrawal from the lever I. The lever I is 10 formed of spring metal, so that it may be readily sprung sufficiently to clear the shoulder j^8 . When therefore this mechanism is in position to form the line lock, it may be released by grasping the button at the end of 15 the pin h^4 and drawing the same outwardly, the lever and pointer H forming a spring permitting this movement. This will permit the shoulder j^9 to pass back of the lever I. A further movement of the stop would bring 20 the shoulder j^9 into contact with the lever I and effect a second swinging of this lever to form a second or final line lock.

It will be noted that the button for effecting the line lock is directly in front of the operator at the platen end of the type basket. It will also be noted that the platen may be moved so as to form the desired margin and the stop may then be moved along the scale to the pointer, thus facilitating the adjustment 30 of the marginal stops. This is especially true in as much as the printing point and marginal stop are visible to the operator at the same time. By placing the adjustable feature on the carriage it may be moved to different positions to facilitate its adjustment.

What I claim as new is:—

1. In a typewriter, the combination of a plate arranged to carry a marginal stop, said 40 plate being provided with a series of notches; a marginal stop arranged on said plate comprising a plate j having the ears j' extending over and engaging the plate carrying the marginal stop; the latch j^3 arranged on the 45 plate j ; the pin j^5 carried by the latch and arranged to engage said notches; the shoulder j^7 on the latch, said shoulder being bent forward from the metal forming the latch; and the spring j^6 tensioned against the shoulder, said spring being arranged on the face of the plate.

2. In a typewriter, the combination of the platen having the printing point in view; a scale for indicating the position of the platen carried by the carriage; a marginal stop carried by the scale; means for adjusting the stop on the scale, the printing point on the platen, and the corresponding point on the scale being simultaneously in view; and 55 mechanism coöperating with said parts to permit of the adjustment of the stop on the scale corresponding to the printing point while both the desired stopping point on the

platen and the corresponding point on the scale are in view.

65

3. In a typewriter, the combination of a platen with a printing point normally in view; a basket arranged for a "front strike" on the platen; a scale carried with the platen; a marginal stop arranged on the scale; and a frame stop arranged in the path of the marginal stop, said frame stop being placed within the segment of a circle of which the basket forms the arc printing point, scale, marginal stop and frame stop 75 being simultaneously in view.

4. In a typewriter, the combination with a platen; of a type basket in the form of a segment; type bars in the basket arranged to strike at the front of the platen; a carriage; a stop on the carriage; a line lock actuated by the stop; a release mechanism for said line lock and an operating button arranged at the platen end of the basket directly above and on said mechanism, said 80 button being centrally located with relation to the segment in front of and directly below printing point on platen.

5. In a typewriter, the combination with the carriage scale carried by the carriage; of 90 a universal bar; devices locking said universal bar against action; and adjustable means on the scale for actuating said devices.

6. In a typewriter, the combination with the platen; of a type basket arranged for a 95 "front strike" on said platen; a carriage; a stop on the carriage; a line lock actuated by the stop; a release mechanism for said line lock having its operating button arranged at the platen end of the basket in front of and 100 below the printing point and intermediate the ends of the segments; and a second stop on the carriage for actuating the line lock after a release.

7. In a typewriter, the combination with 105 the carriage; of a marginal stop thereon; the universal bar; the pointer H comprising the pointing finger h^5 and the spring arms h^3 ; the lever I extending by the spring arms and having the slot i therein; a locking shoulder i^4 thereon adapted to be brought under the universal bar as the lever is moved; and the pin h^4 extending through the pointing finger and the slot i for swinging the lever I out of the path of the stop for releasing the same.

115

8. In a typewriter, the combination of the carriage; the scale F on the carriage, having the notches f therein; the marginal stop comprising the plate J with the ears j' extending over the edges of the scale for securing the plate thereon; the pin j^5 adapted to engage the notches f ; the latch j^3 carried by the plate j and to which the pin j^5 is secured; a spring j^6 tensioned against the latch and holding the pin normally in engagement; 120 the universal bar; the lever I having the slot 125

i therein and the locking shoulder *i* thereon adapted to be brought under the universal bar, said lever *I* being arranged in the path of the plate *j*; the pin *h*⁴ extending through the slot *i* and adapted to draw the lever *I* from contact with the end of the plate *j*; and a shoulder *j*⁹ on the plate *j* for effecting the final stop.

In testimony whereof I have hereunto set my hand in the presence of two subscribing witnesses.

JOHN W. PAUL.
